UNITED STATES PATENT OFFICE.

FRIEDRICH MUELLER, OF ST. LOUIS, MISSOURI.

BRICK-PRESS.

No. 826,438.

Specification of Letters Patent.

Patented July 17, 1906.

Application filed August 5, 1905. Serial No. 272,939.

To all whom it may concern:

Be it known that I, FRIEDRICH MUELLER, a subject of the Emperor of Germany, and a resident of St. Louis, Missouri, have invented 5 certain new and useful Improvements in Brick-Presses, of which the following is a specification.

My invention relates to improvements in a brick-press; and it consists of the novel features hereinafter described and claimed.

The object of my invention is to construct a machine for forming and pressing brick out of dry clay and to expel the pressed form from the machine automatically.

15 A further object of my invention is to provide a mechanism whereby the tension or pressure applied to the dry clay may be adjusted to the desired degree of pressure for forming a brick.

20 In the drawings, Figure 1 is a side elevation of my complete invention. Fig. 2 is a top plan view of the same. Fig. 3 is a vertical longitudinal sectional view taken on the line 3 3 of Fig. 2. Fig. 4 is a side elevation 25 of my invention opposite to that of Fig. 1. Fig. 5 is an end elevation of my invention viewing the same in the direction indicated by the arrow 5 in Fig. 1. Fig. 6 is a vertical cross-sectional view taken on the line 6 6 of 30 Fig. 2. Fig. 7 is a detail perspective view of one of the side brackets made use of for raising and lowering the upper set of dies. Figs. 8 and 9 are detail views of the cams made use of in carrying out my invention. Figs. 10, 35 11, 12, and 13 are vertical sectional views of a portion of the machine, showing the positions of the dies and operating-cams during the method of forming a brick. Figs. 14 and 15 are a plan and side elevation of the adjusting device.

40 In the construction of my invention I provide a suitable frame 14, mounted upon a base 15. The upper portion of the frames are connected to a table 16, composed of 45 two parts, and in the intervening space between the two sections is located the mold 17, in which the brick is formed. Upon the top of the table and to one side of the mold is located a hopper 18, in which the clay 50 is placed and from which it is fed into the mold by means of a conveyer 19. The conveyer 19 is provided with pockets 20, by which the clay is fed from the hopper 18 into the mold 17, the operation of which 55 will be fully hereinafter described. In the

frames 14 are provided suitable journals 21, in which is revolvably mounted an operating-shaft 22. On this shaft is mounted a large gear-wheel 23, with which meshes a pinion 24, mounted upon a driving-shaft 25, supported in suitable bearings formed in the frame 14 and placed in operation by means of the pulley-wheel 26.

Upon the operating-shaft 22 are mounted the cams 27 and 28, the cams 28 being located 65 one on each side of the cam 27 and being designed to come in contact during the revolution of the shaft 22 with the rollers 29, mounted upon a shaft 30, which shaft is supported in a pair of side brackets 31, one located on each side of the machine-frame and guided between ribs 32. The upper ends of the side brackets 31 are bent inwardly and securely fastened to a die-head 33, to the under surface of which is provided a pair of dies 34, 70 75 which operate in the mold 17, in which the clay is pressed.

The cam 27 during the operation of the machine is designed to come in contact with the roller 35, which is located in a die-block 80 36, which operates a pair of dies 37, formed on the upper surface of said block, and which presses the clay within the mold 17 in conjunction with the pressure brought upon the clay from the dies 34. The die-block 36 is 85 guided between the ribs 38, formed on the inner surface of the frames 14, and is adjusted to the required movement by an adjusting device 39, which consists of a bifurcated frame 40, having inclined surfaces 41, which 90 is brought in contact with the under surfaces of the side portions of the die-block 36. The bifurcated frame 40 is located and guided upon bars 42, formed on the inner surface of the side frames 14, and said bifurcated frame 95 is held in position by a cross-bar 43, securely bolted to the side frames 14. To the cross-bar 43 is mounted an operating-screw 44, which is screw-threaded, and by the manipulation of the hand-wheel 45 will operate the 100 bifurcated frame 40 inwardly and outwardly, as desired, to raise and lower the die-block 36 to any height desired.

Upon the operating-shaft 22 and located on the outside of the frames 14 are provided 105 cams 46, which during the revolution come in contact with the rollers 47, carried by the side brackets 31, which raise and lower the brackets by the contact of the cams and raise and lower the dies 34 in and out of the 110

2
mold 17 for the admission of the clay and to press the same. The vertical motion of the side brackets 31 is permitted by means of the elongated slots 48. In the gear-wheel 23 is 5 formed a camway 49, in which operates a roller 50, carried by a lever 51, mounted upon a shaft 52, which extends through the side frames 14, and on the opposite end of said shaft is connected a lever 53. On the upper 10 ends of the levers 51 and 53, which are located in alinement with each other, are provided elongated slots 54, and through said slots project a shaft 55, which extends through the conveyer 19 and by the manipulation of 15 the levers 51 and 53 feeds the clay from the hopper 18 into the mold 17. This operation is done by the formation of the camway 49 and at a period when the upper dies 34 are in elevated position, so that the conveyer may 20 freely pass beneath the dies 37 to remove the brick which has been previously pressed and at the same time to refill the mold for a repeated compression. The conveyer 19 is held in position upon the table by means of 25 the guide 56.

The operation of my invention is as follows: The clay, which may be either in a dry or moistened state, is placed within the hopper 18, which will necessarily fill the pockets 30 20 of the conveyer, and while the upper die is in its raised position and at that period by the manipulation of the camway in the gear-wheel will operate the levers 51 and 53, bringing the conveyer 19 forward over the mold 17 35 and permitting the clay carried by the pockets 20 to fall within and fill up the mold 17, and during its return the sides of the pockets act as a scraper to remove from the mold all surplus clay. At the instant the conveyer is 40 brought to its normal position the upper dies 34 begin to descend by means of the cams 28 coming in contact with the rollers 29, pulling downwardly upon the side brackets 31. At this instant the center cam 27 comes in contact with the roller 35, slightly raising the die 37, which imparts an upward compression 45 upon the clay within the mold 17. Then the highest point of the cam 27 begins to raise the die-block 36 and dies 37, and at the same time the highest part of the cam 28 is released 50 from the rollers 29, and the cams 46 begin to contact with the rollers 47, raising the side brackets 31. During this period both dies 34 and 37 simultaneously rise until the contact-surface of the die 37 is in a horizontal plane 55 with the table. At this period the form of compressed clay is delivered from the mold. Then the conveyer begins to advance and pushes the form forward and automatically 60 fills the mold for a second compression. The abrupt offset 57 formed in the cam 27 is to permit the die 37, die-block 36, and roller 35 to 65 its normal position at the moment the fall brick is removed from the mold and provide sufficient space for the refilling of the mold

by the conveyer. The rotation of the machine is in the direction indicated by the arrow X.

In Figs. 10, 11, 12, and 13 the machine is shown in its four distinct operations. Fig. 70 10 shows the lower die in elevated position, the compressed form of clay being delivered from the mold, and the conveyer in the act of passing over the mold ready to fill the same. Fig. 11 shows the lower die in its 75 lowest position, the mold filled with clay, the compressed form removed from the mold and resting upon the table, and the conveyer ready to be brought back to its normal position. Fig. 12 shows the mold filled with clay, 80 the upper die descending and in the act of compressing the clay within the mold. Fig. 13 shows both of the dies in their compressed position and the clay within the mold compressed to the form desired. The next operation will be similar to Fig. 10.

Having fully described my invention, what I claim as new, and desire to have secured to me by the grant of Letters Patent, is—

1. A brick-press of the class described, 90 comprising a suitable frame, an operating-shaft located within said frame, a plurality of cams located upon said shaft, a gear-wheel, a pair of side brackets guided in said frame, dies carried by said brackets, a table mounted 95 between said frames and operated by one of said cams, rollers carried by the side brackets and operated by two of said cams carried by the operating-shaft, a feeding mechanism for filling 100 the molds formed in the table, a cam formed in the gear-wheel to operate the feeding mechanism, and to remove the compressed form of clay delivered from the mold simultaneously, and means for operating said dies 105 and feeding mechanism, substantially as specified.

2. A brick-press of the class described, 110 comprising a frame mounted upon a base, an operating-shaft operating in said frame, a plurality of cams located upon said shaft, a table, molds formed in said table, a pair of side brackets guided in said frame, a pair of dies carried by said side brackets, a die-block located within the frame, and operating from 115 beneath the table, a roller located in said die-block and connecting with the center cam on the operating-shaft, a roller carried by the side brackets and communicating with the cams located on each side of the center cam of the 120 operating-shaft, which imparts downward motion to the upper dies, a pair of cams located upon the operating-shaft at the outside of the frame, rollers carried by the side brackets and communicating with said cams for 125 imparting upward motion to the upper dies, a conveyer mounted upon the table to convey the clay into the mold and simultaneously remove the compressed block from the lower die, and a gear-wheel provided with a 130

cainway located upon the operating-shaft for manipulating the conveyer, substantially as specified.

3. A brick-press of the class described, comprising a frame mounted upon a base, an operating-shaft operating in said frame, a plurality of cams located upon said shaft, a table, molds formed in said table, a pair of side brackets guided in said frame, a pair of dies carried by said side brackets, a die-block located within the frame, and operating from beneath the table, a roller located in said die-block and connecting with the center cam on the operating-shaft, a roller carried by the side brackets and communicating with the cams located on each side of the center cam of the operating-shaft, which imparts downward motion to the upper dies, a pair of cams located upon the operating-shaft at the out-

side of the frame, rollers carried by the side brackets and communicating with said cams for imparting upward motion to the upper dies, a conveyer mounted upon the table to convey the clay into the mold and simultaneously remove the compressed block from the lower die, a gear-wheel provided with a camway located upon the operating-shaft for manipulating the conveyer, and an adjusting device carried by the frame for adjusting the position of the lower dies, substantially as specified.

In testimony whereof I have signed my name to this specification in presence of two subscribing witnesses.

FRIEDRICH MUELLER.
